UNITED STATES PATENT OFFICE.

JOSEPH SAILER, OF OXNARD, CALIFORNIA.

REGULATING DEVICE FOR WASHING SUGAR.

1,181,259.

Specification of Letters Patent. Patented May 2, 1916.

Application filed August 17, 1911, Serial No. 644,720. Renewed June 8, 1914. Serial No. 843,906.

To all whom it may concern:

Be it known that I, JOSEPH SAILER, a citizen of the United States, and a resident of Oxnard, in Ventura county and State of California, have invented certain new and useful Improvements in Regulating Devices for Washing Sugar, of which the following is a specification.

This invention pertains to regulating devices, and it has special reference to means for regulating the supply of water used in washing sugar in the centrifugal machines, and for automatically shifting the syrup spout, although the invention contemplates a wider range of use, since the regulating and feeding mechanism may be employed for any and all purposes other than specifically stated herein.

In the process of manufacturing sugar, part of it goes to what is called the green, and part to the wash, and it is the object of this mechanism to provide a means whereby the water for washing the sugar may be regulated so that a greater or less amount of water will be furnished by the machine during the process and also to shift the syrup spout.

The piston of the cylinder is regulated as to the extent of its motion by a pair of fingers, which project inwardly. These fingers are connected with a bar which is capable of being set at any point so that it limits the stroke of the piston, and the four-way valve supplies water to the cylinder, so that it automatically moves the piston back and forth by the reversing portion of the lever connected with the four-way valve, as will now be set forth in detail:

In the drawing Figure 1 is a plan view of the regulating device for washing sugar, and Fig. 2 is a side elevation of the discharge spout.

In constructing my invention I provide a long horizontal cylinder 3, with the heads 4 and 5, each of which has a stuffing box 6, and through this cylinder is a piston rod 7, having the usual piston 8. At each projecting end of the piston rod 7, is a laterally projecting arm 8', which carries a pair of parallel rods 9, 10. Each parallel rod 9 and 10 has thereon an adjustable dog 11, provided with a trip finger 12 on its lower side.

Below the rods 9 and 10, and on a line midway between the ends of the cylinder 3 is a horizontal, transversely disposed, rock-

shaft 13 mounted on bearings 14, and one end of this shaft 13, which terminates at a point between the rods 9 and 10, is a vertical standard 15, which carries at its upper end 60 a pair of oppositely projecting arms 16, slightly curved, as shown, which arms are designed to engage with the tripping fingers 12, on the rods 9 and 10.

The horizontal rock-shaft 13 is designed 65 to carry the syrup spout 17, which is suspended on a bail 18. The upper end of the bail has a vertical slot 19, so that it may be vertically adjusted a limited distance, as well as swung to any desired angle with 70 reference to the position of the vertical stem 15.

Each of the cylinder heads 4 and 5 has an inwardly-projecting stem 20, which passes through suitable stuffing boxes, as at 75 21, and these stems are held at their outer ends by downwardly projecting arms 22, the upper ends of which slide loosely on a guide arm 23 attached to the parallel projecting brackets 24 integral with the cylinder 80 heads.

Intermediate the stem 20, and guide rod 23 is a rod 25, which passes through the bracket 24, and a pair of collars 26 on the opposite sides of one of the brackets 24 85 serves to prevent longitudinal movement of this rod. The rod 25 also passes through the threaded openings in the arms 22. The rod 25 is provided at its opposite ends with right and left hand screws, so that when 90 the rod 25 is turned by the hand wheel 27, in either direction, the arms 22 are both moved and thus cause the stems 20 to simultaneously move inwardly or outwardly, as the case may be, and limit the reciprocating motion of the piston 8.

A gage 28 is attached to one of the fingers 22, as shown at 29, and projects over one of the brackets 24, and a finger 30 attached to the cylinder head 5, serves to indicate either 100 the distance that the stem 20 projects into the cylinder, or it may serve to indicate the quantity of water which the cylinder will contain between the ends of the stems 20. For this purpose the gage has vertical 105 division lines or marks, as shown, which pass beneath the indicating finger 30.

The cylinder is supplied with water through the main inlet pipe 31, which connects with the four-way valve 32, each cylinder head being connected up with the four-way valve by a pipe 33, and the dis-

charge end of the four-way valve has a hose 34.

The operating lever 35, of the valve, which is designed to reverse the piston, is limited in its swinging motion by stops 36, placed at suitable points.

- The operation of the device is as follows: Water is supplied to the apparatus through the inlet pipe 31, and we will assume that 10 the operating lever 35, of the four-way valve, is swung to the right, as indicated by the dotted lines in Fig. 1. In that case the water enters the cylinder at the right hand end, through head 5, driving the piston to 15 the left, while the water contained behind the piston at the same time passes out through the head 4, and back to the four-way valve 32, discharging through the hose 34.
- 20 As it is very important to have the requisite quantity of water for washing purposes, the stems 20 are moved in or out, as desired, so that the gage will indicate the quantity of water discharged.
- 25 At the same time the piston rod 7, in its movement back and forth, carries therewith the parallel rods 9 and 10, and as the dog

11 is adjustably connected with these bars, the fingers 12, connected therewith, come into engagement with the arms 16, which 30 rock the spout 17, so that each tripping finger 12 will cause the syrup spout to swing in only one direction, and by means of which the swinging position or movement of the spout may be changed to take effect at any 35 point in the stroke of the piston.

What I claim as new, is:—

In a regulating device for washing sugar, a cylinder having a piston rod therethrough, a piston mounted on said rod an inwardly-projecting stem through each cylinder head, means for simultaneously moving said stems inwardly to limit the stroke of the piston, and a gage for indicating the quantity of liquid discharged at each stroke of the piston.

Signed at the city and county of Los Angeles, State of California, this 18th day of May, 1911, in the presence of witnesses.

JOSEPH SAILER.
